(57) **CLAIM**

I claim the ornamental design for a pourer device, as shown and described.

DESCRIPTION

FIG. 1 is a side elevational view of the novel pourer device, the other side being identical to the view shown;

FIG. 2 is a front elevational view of the pourer device;

FIG. 3 is a rear elevational view of the pourer device;

FIG. 4 is a top plan view of the pourer device; and,

FIG. 5 is a bottom plan view of the pourer device.
